UNITED STATES PATENT OFFICE

OTTO VOGL, OF CHICAGO, ILLINOIS

DESIGN FOR A RIBBON-SPOOL HOLDER OR THE LIKE

Application filed June 13, 1929. Serial No. 31,674. Term of patent 14 years.

To all whom it may concern:

Be it known that I, OTTO VOGL, a citizen of the United States, residing at Chicago, in the county of Cook and State of Illinois, have invented a new, original, and ornamental Design for Ribbon-Spool Holder or the like, of which the following is a specification, reference being had to the accompanying drawing, forming a part thereof.

The figure is a perspective elevational view of the ribbon spool holder.

I claim:

The ornamental design for ribbon spool holder, or the like, substantially as shown.

OTTO VOGL.
